UNITED STATES PATENT OFFICE.

NATHANIEL M. ORR AND GEORGE D. SNIDER, OF BLACKSBURG, VIRGINIA.

DETACHABLE-BLADED RAZOR.

1,269,497.

Specification of Letters Patent. Patented June 11, 1918.

Application filed June 20, 1917. Serial No. 175,925.

To all whom it may concern:

Be it known that NATHANIEL M. ORR and GEORGE D. SNIDER, citizens of the United States, residing at Blacksburg, in the county 5 of Montgomery and State of Virginia, have invented certain new and useful Improvements in Detachable-Bladed Razors, of which the following is a specification, reference being had to the accompanying drawings.

This invention relates to razors and particularly to that type of razor in which the blade shank is pivotally connected to a handle, so that the shank may be turned either 15 into operative position or into a position within and housed by the handle.

The general object of the invention is the provision of very simple means whereby the blade may be detachably held to the shank 20 so that the blade may be readily removed and a new blade inserted.

A further object of the invention is to provide improved locking means for holding the blade in place so that it cannot become 25 loose or detached and still another object is to improve the details of construction of the razor so that it may be cheaply made and so that the parts will be firmly held in their coöperative position.

30 Other objects will appear in the course of the following description.

Our invention is illustrated in the accompanying drawings, wherein:—

Figure 1 is a side elevation partly in section of a razor constructed in accordance 35 with our invention;

Fig. 2 is a top plan view of the shank of the razor, the latch being in section;

Fig. 3 is a section on the line 3—3 of 40 Fig. 1;

Fig. 4 is a perspective view of the latch;

Fig. 5 is a side elevation of the blade detached.

Referring to these drawings, 10 designates 45 the usual handle of razors of this type formed of two spaced strips. Pivotally mounted upon a pin or rivet 11 is the shank 12 of the razor, this shank having a solid tang 13 extending rearward therefrom and 50 formed to fit the finger, as is usual. This tang is preferably made of a strip of metal bent upon itself, so as to be approximately U-shaped in cross section, the space in the tang rearward of the pin 11 being filled or 55 otherwise rendered solid, as heretofore stated. Extending through the lateral walls

of this tang are the rivets 14, two of these rivets being shown. One side wall of the tang is formed with a slightly projecting inwardly extending boss 15 which may be 60 formed by pressing the side wall inward.

The blade 16 has, to all intents and purposes, the form of an ordinary razor blade, but its back is provided with two bayonet slots 17, which are adapted to coact with the 65 pins or rivets 14. The inner end of the blade is rounded at 18, but at its inner corner the blade is formed with a slight projection or lug 19. Outward of this lug the end of the blade is flat.

70 For the purpose of holding the blade in place, we provide a locking member or latch 20. This is formed of a strip of metal approximately T-shaped in cross section which at one end is reduced and formed with a 75 perforation through which passes the rivet or pin 11 so that the latch 20 is pivoted to the shank 12. The lower edge of the latch has the laterally extending flange 21, but the body of the latch may be inserted between and fill up the space between the side walls 12. The free end of the latch is straight, as at 22, but the inner corner of this free end is rounded as at 23. The metal of which this latch is made is provided with a depression 24, which, when the latch is swung into place between the side walls of the shank 12 is engaged by the inward projection 15 and this locks the latch in its operative position. Preferably the 80 outer face of the flange portion 14 is toothed or serrated.

85 In the practical use of this device, the blade is disposed with its slots in engagement with the pins or rivets 14 and then 90 shifted longitudinally to the position shown in Fig. 1 and then the latch 20 is swung inward, its end face 21 engaging with the flat portion at the end of the blade and engaging with the lug 19, so as to hold the 100 blade securely in place and in locked engagement. When it is desired to remove the blade, it is only necessary to retract the latch by hand and then the blade may be readily withdrawn. The retraction of the 105 latch is easily accomplished because of its being T-shaped in cross section, the resistance of the detent boss 15 being only sufficient to hold the latch from accidental detachment. Thus it may be seen that a new 110 blade may be easily substituted for an old blade, so as to permit the old blade to be

ground by machinery. It would seem that the construction which we have provided is very simple, may be cheaply made and that the blade is held very firmly and solidly in place and, furthermore, that the blade is held from any outward movement by the engagement of the bayonet slots with the rivets 14 and not by a mere engagement of the latch with the end of the blade.

10 Having thus described our invention, what we claim is:—

15 A razor including a handle and a hollow shank, a pivot pin running through the handle and the shank and pivotally connecting the same, transversely extending rivets disposed through the shank, a blade having bayonet slots on its back engageable with said rivets, the inner end of the blade at its back marginal portion being provided with

20 a lug extending outwardly of the blade, and a latch pivoted on said pivot pin and swinging thereon into the hollow shank to engage the rear end of the blade and overlie the lug of the blade whereby said blade is prevented from being shifted to disengage it from the 25 rivets, said latch being T-shaped in cross section, opposed faces of the latch and shank being provided with co-acting means for holding the latch in engagement with the inner end portion of the blade.

30

In testimony whereof we hereunto affix our signatures in the presence of two witnesses.

NATHANIEL M. ORR.
GEORGE D. SNIDER.
